UNITED STATES PATENT OFFICE.

WILLIAM PATON, OF JOHNSTONE, COUNTY OF RENFREW, SCOTLAND.

DESIGN FOR AN EXHIBIT FOR SHOE-LACES.

SPECIFICATION forming part of Design No. 18,303, dated May 8, 1888.

Application filed July 13, 1887. Serial No. 244,206. Term of patent 14 years.

To all whom it may concern:

Be it known that I, WILLIAM PATON, a subject of the Queen of Great Britain and Ireland, and a resident of Johnstone, in the county 5 of Renfrew, Scotland, have invented a new and useful Design for Exhibit of Boot and Shoe Laces, of which the following is a specification.

My design for an exhibit of boot and shoe laces is fully shown in the accompanying drawing, representing a front perspective view of the exhibit.

My design comprises an exhibit of laces, B, made up into parallel pairs and having knots 15 *f* at short distances from both ends.

I claim—

The herein-described design for an exhibit of laces, comprising laces made up into parallel pairs, and having knots *f* at short distances from both ends, substantially as shown and set forth.

In testimony whereof I have signed my name to this specification in the presence of two subscribing witnesses.

WILLIAM PATON.
